(57) **CLAIM**

The ornamental design for a trellis, as shown and described.

DESCRIPTION

FIG. 1 is a perspective view of my new trellis design;
FIG. 2 is a top plan view of the trellis of FIG. 1;
FIG. 3 is a front elevation view of the trellis of FIG. 1;
FIG. 4 is a left side view of the trellis of FIG. 1;
FIG. 5 is a bottom plan view of the trellis of FIG. 1; and,
FIG. 6 is an enlarged fragmented perspective view of the
free end segment viewed in FIG. 1.

The back elevation view is a mirror image of FIG. 3, while
the right side view is identical to FIG. 4.
